UNITED STATES PATENT OFFICE.

CARL H. CULVER, OF DETROIT, MICHIGAN, ASSIGNOR TO CULVER STEARNS MANUFACTURING COMPANY, OF WORCESTER, MASSACHUSETTS, A CORPORATION OF MASSACHUSETTS.

SUPPORT FOR CONCEALED DASH LAMPS.

Application filed April 17, 1926. Serial No. 102,776.

This invention relates to a device for supporting a dash lamp for an automobile which is mounted in a position in which the lamp itself is invisible from the front of the dash.

The principal objects of the invention are to provide a device for supporting the lamp in such a way that the lamp can be withdrawn from the outer side of the dash without disconnecting the lamp so that a new lamp can be put on and other repairs made without access to the lamp in front of the dash; to provide this support in a simple and inexpensive form and arrange it with means for holding the lamp socket in position and yet capable of yielding to allow it to be withdrawn or inserted by motion in a straight line.

Other objects and advantages of the invention will appear hereinafter.

Reference is to be had to the accompanying drawings in which

Fig. 1 is a cross section of a concealed lamp and a part of the dash with a preferred form of this invention in position for holding the lamp;

Fig. 2 is a full sized end view of the holding device; and

Fig. 3 is a sectional view of the same on the line 3—3 of Fig. 2.

It is customary at the present time to have the dash lamp concealed by mounting it in a box or casing 10, behind the dash 11 and in such a position that an opaque part of the dash is directly in front of the lamp. A metal reflector 13 is used to disperse the light through a glass 14, which is permanently fixed on the dash so that it cannot be removed when the lamp has to be replaced.

I have shown the invention as employed in connection with such features and also with a clock, gauge, or other instrument 15, also in the casing 10.

For the purpose of holding the socket 18 for the lamp 12, I make a very inexpensive sheet metal holder comprising a horizontal flange 16 and three spring arms 17, all formed of a single piece of sheet metal. The flange projects at two ends and is welded to the metal box or casing 10, by the spot welding process or any other way. The lamp holder is provided with a passage all the way through for the insertion of the lamp

and its socket. The holder has a circular rib 19 around it at a certain point. The spring arms 17 are provided with offset portions 55 which have on the back, indentations or grooves 20 located in the right position to register with and receive the rib 19 so that they constitute a spring holder for the socket 18. The arms are slanted off at the ends 60 to permit the socket to be inserted. I have shown the electrical cable 21 for feeding the lamp.

In the use of the device, the lamp 12 is put in its socket 18 outside and then it is moved 65 in from the back along the axis of the hole in the flange 16 until the rib 19 enters the grooves 20. This method of insertion offers little resistance and when the grooves 20 receive the rib on the lamp socket the lamp will 70 be held in position so that it will not become dislodged. These spring arms hold it with a yielding pressure and absorb some of the shocks to which the lamp ordinarily is submitted.

When it is desired to remove the lamp from the socket they are pulled out by a straight backward motion as will be obvious.

I am aware of the fact that the invention is not limited to dash or automobile lamps. 80 Although I have shown only a particular form of the invention and shown it applied to a particular lamp socket I am aware of the fact that modifications can be made therein by any person skilled in the art without departing from the scope of the invention as expressed in the claim. Therefore, I do not wish to be limited in these respects, but what I claim is:

The combination with an automobile dash, 90 a casing set therein, a lamp in the casing, a reflector curved around the lamp for concealing it and directing its rays in one direction, and a transparent cover at one side of the reflector permanently mounted on the 95 dash, of means at the back of the casing behind the reflector for holding a lamp in a position to be concealed by the reflector and arranged to receive the lamp and its socket from the rear.

In testimony whereof I have hereunto affixed my signature.

CARL H. CULVER.
